 PC(57) **CLAIM**

What is claimed is the ornamental design for an extruded channel, as shown and described.

DESCRIPTION

FIG. 1 is a front perspective view of an extruded channel showing our new design.

FIG. 2 is a rear perspective view of the extruded channel of FIG. 1.

FIG. 3 is a right side elevation of the extruded channel of FIG. 1, the left side elevation view being a mirror image thereof.

FIG. 4 is a front elevation view of the extruded channel of FIG. 1.

FIG. 5 is a top plan view of the extruded channel of FIG. 1.

FIG. 6 is a bottom plan view of the extruded channel of FIG. 1; and,

FIG. 7 is a rear elevation view of the extruded channel of FIG. 1.

The extruded channel is shown with a symbolic break in its length. The appearance of any portion of the extruded channel between the break lines forms no part of the claimed design.
